UNITED STATES PATENT OFFICE.

DAVID B. BIRD, OF CHICAGO, ILLINOIS.

FOWL-DISINFECTANT APPARATUS.

1,230,843.

Specification of Letters Patent. Patented June 26, 1917.

Application filed October 14, 1916. Serial No. 125,613.

To all whom it may concern:

Be it known that I, DAVID B. BIRD, a citizen of the United States, residing at Chicago, in the county of Cook, and State of Illinois, have invented certain new and useful Improvements in Fowl-Disinfectant Apparatus, of which the following is a specification.

The invention relates to means for causing fowls to subject themselves to the operation of a disinfecting device. It has for an object to provide such a device which can be easily erected in any convenient situation. It is a particular object to provide a device of this character which is adaptable to use with either liquid or powder disinfectant. A further important object is to give a device of this character which will not tend to waste the disinfectant, and will tend to cause a fowl to leave the device as soon as it has been subjected to one treatment.

An important aim of the invention is to give an improved mounting and construction for such a device, and it is an especial advantage thereof that it is adjustable to accommodate fowls of different weight, the weight of the fowls being used to operate the device.

My appliance has also the advantage that it induces a considerable amount of exercise in fowls, and may be used for that purpose alone, when not employed as a disinfectant device.

It is a particular object to give a desirable construction in a device for automatically spraying a fowl with powder or liquid disinfectant. It is also an aim to give a desirable, specific construction in a fowl operated blowing device. Another object is to give an improvement in nozzle devices for such purposes.

Additional objects, advantages and features of invention will appear in the construction, arrangement, and combination of parts hereinafter set forth, and shown in the drawings, where—

Figure 1 is an elevational view of a device constructed in accordance with my invention,

Fig. 2 is a detail sectional view of the blower device,

Fig. 3 is a top plan view of the blower device,

Fig. 4 is a sectional detail view of the nozzle and roost mounting and construction,

Fig. 5 is a rear view thereof,

Fig. 6 is a detail of the extensible joint of the roost lever,

Fig. 7 is a detail section of a modified form of blower device, 60

Fig. 8 is a detail of a form of nozzle device for use with the appliance,

Fig. 9 is an elevation of a modification,

Fig. 10 is a fragmentary elevation of a further modification, 65

Fig. 11 is a detail of a nozzle,

Fig. 12 is a detail of a container of disinfectant.

In order that the device may be conveniently used either out of doors or in a poultry house or other place, it is mounted upon a board 10, with a cross piece 11, forming a base somewhat in the form of the letter T. The appliance in this embodiment includes a resiliently supported lever 12, normally extending diagonally upward toward its forward end, where a short transverse perch 13 is provided. What I term a puff-ball 18 is associated with the base of the lever in such manner that oscillation of the lever in one direction will compress the ball, blowing air through the lever itself, which is hollow, to a nozzle 15 at the outer end of the lever, so directed as to project any material passing therethrough upon the body of a fowl on the perch, especially upon the legs of the fowl and its rear part, the fowl being headed toward the base of the lever.

The mounting of the lever in the present case comprises a heavy strip of sheet metal having its central portion bent so as to form a partly cylindrical portion 16, the end portions being abruptly turned outwardly in a common plane to set snugly upon the upper surface of the board 10, and at a distance from the first point of outward bending the end portions are bent upwardly and inwardly and attached to the adjacent circular portion forming braces 17. The circular 95

part has snugly fitted therein a rubber ball 14, which is preferably supported on the interior by a suitable spring 19 to hold it distended, and the ball is provided with a suitable connection at one side, as at 20, 105 from which a hose 21 is led. The metal 16 is resilient, and at the forward side is slotted as at 22, forming a spring tongue 23, which may be pressed inwardly to bear against the ball for expulsion of its contents. The 110 tongue 23 has secured thereon a suitable heavy plate 24, provided with a centrally

recessed boss 25, interiorly threaded, in which is screwed a section of pipe 26, forming the inner or lower end of the lever 12. The boss 25 is provided with a lateral extension or nipple 27, having an opening therethrough communicating with the bottom of the recess in the boss 25, so that communication with the interior of the pipe 25 may be formed through this nipple. The 10 hose 21 is fitted over the nipple, so that when the ball 14 is compressed the contents are expelled through the hose 21 into the pipe 26. Engaged slidably upon the forward end of the pipe 26 there is a telescopic pipe 15 section 27, having its inner end slit a short distance and provided with a binding nut or collar 28, screwed thereinto, in order to tighten the pipe 27 upon the one 26 and hold it in adjusted position. Suitable packing 20 means may be provided as at 29, or elsewhere in the telescopic joint, as found desirable. Engaged upon the pipe 26 inwardly of the collar 28 there is a slidable collar 30, having an eye 31 at its upper side for engagement of a cord or cable 32, which is extended therefrom upwardly over a pulley 33 and downwardly a distance immediately inward of the outer end of the pipe section 27, to support a cabbage head 34 or other suitable food, for a purpose to be explained. The collar 30 is also provided with a set screw 35 by which it may be secured in adjusted positions.

Slidable upon the outer part of the pipe 35 section 27 there is a collar 36 secured by means of a binding screw 37 and having trunnions 38 extending horizontally at each side, on which there are pivoted arms 39 carrying a short perch 13, before mentioned. The arms are connected by a cross tie 40 spaced intermediately thereof, a lug 41 being provided on the collar 36 to engage this cross tie to limit pivotal movement of the perch toward the outer end of the pipe 27. The perch is kept yieldably in this position by means of a small spring 42 connected to the arm 39 at one side and having an arm 43 bearing slidably upon the collar 36 at its inner part. The outer 50 end of the pipe 27 is threaded and has engaged thereon the nozzle before mentioned, the base of which is suitably enlarged and interiorly threaded for engagement on the outer end of the pipe 27. The construction 55 of the nozzle may be of any suitable and well known kind used for the purposes in view, there being well known devices for spraying powder and also others for spraying liquids which may be adapted, as required. It is to be noted that in the initial 60 position of the perch 13, its forward edge is very close to the tip of the nozzle, this edge of the perch being recessed to prevent the tip of the nozzle from being closed. The tip of the nozzle is located

approximately on a level with the upper side of the perch, although this exact relation is not essential.

In Fig. 7 there is shown a modification of this device with respect to the mounting of the lever, in which the inner section 26' of the pipe is carried upon a hinged tongue 23', movable in the circular part 16' of a rigid base element similar to that first described. In this case, the pipe 26' is mounted as before described, but the puff ball 14' is provided with a neck portion 50, extended through a suitable opening in the hinge plate. The neck portion 50 is extended through a suitable opening 80 in the hinged plate, and into the boss 25', upon which the pipe 26' is screwed. The neck of the ball is secured tightly in any suitable manner to prevent escape of air therearound; in the present case, a metal collar 51 being inserted in the neck, so as to pack it tightly against the inner sides of the boss 25'. In the side of the puff ball a suitable inlet and check valve 14' is provided, of any suitable kind. A similar check valve may be utilized with the various other forms of the device, if desired, although it is thought that it may be omitted in some instances and replenishment of air in the ball effected through the 85 nozzle, without detriment.

In use, the device is installed substantially in the manner illustrated in Fig. 1. The pulley 33 may be mounted upon a suitable standard 14, extending from the board 10 upwardly some distance above and to the rear of the perch 13. The pulley 33 may be suspended from any other suitable support.

In practice, the perch is held yieldably at an elevation of eighteen inches or more above the floor, according to the size and character of the fowl by action of the spring tongue 23, or the spring 55, shown in Fig. 7, mounted on the under side of the pipe 26' and bearing upon the board 10 thereunder, this spring being shown as a leaf spring, although any other desirable form of spring may be used. The cabbage 34 is adjusted at a distance above the perch when in initial position, such that when a fowl when standing upon the perch in this position may reach the food and partake thereof. The strength of the resilient means supporting the lever 12, however, is such that as soon as a fowl jumps upon the perch, the lever will be borne downwardly and this drawing upon the cabbage 34 will lift the food out of reach of the fowl, so that the fowl will not remain indefinitely upon the perch. Opportunity is thus given a large number of fowls to gain access to the perch in succession and be treated with disinfectant desired and the fowls are also induced to take exercise 130

at frequent intervals in their endeavors to reach the food 34.

It is apparent from the foregoing that an extremely simple and inexpensive fowl disinfectant and exercising device is provided of a durable character and adapted to be produced at a low cost.

It should be noted that when the fowl leaps upon the perch 13, the perch swings forwardly with the momentum of the fowl, so that the fowl becomes so positioned that the disinfecting action of the device is made highly efficient upon those areas of the body of the fowl most desired.

In Fig. 8 there is shown a particular form of nozzle adapted to operate efficiently with my appliance, and to insure efficient discharge of disinfectant. The nozzle in this instance comprises a body casting 45 adapted to be screwed on the end of a pipe as desired, and having a suitable duct therethrough. The outer end of the nozzle body is tapered and pointed upwardly so as to direct material passing therethrough, properly, and at its base is provided with a spring pressed valve 46, by which ingress of air from the pipe 27 through the nozzle will be prevented, until the pressure has risen to a predetermined degree. From the valve the body 45 is extended downwardly, and recurved upwardly to its tip, and disinfectant is supplied to the passage at the lowermost part of the device from a reservoir 47, having communication with the passage through the nozzle by means of a nipple 48, screwed into the nozzle, and serving to support the reservoir 47. A ball 49 is disposed in the reservoir, serving to agitate the powder if such be used under movement of the pipe 27 downwardly when a fowl gains the perch 13. When powder is used, the ball 49 does not require to be of a height to engage over the inner end of the nipple 48 within the reservoir 47.

In Fig. 9 there is shown a modification of the mounting of the device with respect to the puff ball, which consists in providing a suitable supporting frame 50 in which the puff ball 51 may be set, including standards 52, upon which there is pivoted diametrically over the ball a swinging bracket arm 53 having movement to engage the ball and being nearly or quite concentric with the ball at one position. The ball is formed with a small neck 54 inserted through an opening in a partly spherical plate 55, mounted on the end of a pipe 27' corresponding to the pipe 27 before described.

In Fig. 10 there is shown a further modification of the device in which a pipe 27^a is utilized for the function of the pipe 27, the lower end of the pipe only being shown, this being extended in form of a loop 57, engaged around a suitable sleeve 58 engaged 65 revolvably upon a shaft 59 carried in stand-

ards 60 upon the base board 61. The lower end of the pipe 27^a is extended inwardly beyond this loop a distance, and then downwardly as at 62, where it is provided with a centrally apertured normally horizontal disk 63, through which the outlet neck of a ball 64 is engaged, the ball in this instance simply resting upon the board 61.

In Fig. 11 there is shown a form of nozzle suitable for use with the device in such constructions as illustrated in Figs. 8 and 9, this nozzle comprising a base portion 65 having an outer end interiorly threaded for engagement on the end of the pipe, the inner part being suitably shaped to provide a seat for a spring 66 disposed therein and bearing toward the open end of the base upon a ball 67 loosely disposed therein. An annular nut 68 is screwed into the threaded part of the base into engagement with the ball to form a seat therefor, by which means passage of air through the nozzle is resisted until it reaches beyond the desired pressure. The nut 68 is small enough to leave room for the engagement of a pipe in the end of the nozzle outwardly of the nut. The nozzle is extended vertically downward normally, from adjacent the spring 66, where it is then curved upwardly and tapered as at 69, as may be found desirable. In the bight 70 formed at the lower part, a suitable internally threaded extension 71 is formed, extending horizontally, into which the pipe or nipple 48 before described may be screwed.

In Fig. 12 there is shown a form of container for disinfectant suitable for use with the nozzle previously described, consisting of a simple rectangular box 72, having on one end an outlet nipple 73 adapted to screw into the extension 71 of the nozzle, and provided with a valve seat 74 therearound at the inner side through which there is inserted a needle 75, having a valve portion 76 at its base, the stem 77 of which extends longitudinally through the box and is threaded in a suitable fitting 78 at the end of the box opposite the nipple 73. The stem projects from the box adjacent the fitting 78, and has a lock nut 79 engaged thereon by which it may be secured in adjusted position. A cross pin 80 is engaged through the outer end of the stem 77, by which it may be turned for adjustment. A plurality of balls 81 are disposed loosely in the box 72, so that in operation of the device by a fowl, the balls will roll about, and the contents of the box will be agitated.

What is claimed:

1. A lever, resilient means supporting the lever in predetermined initial position, a perch on the lever, a spraying device adjacent the perch for action upon a fowl when on the perch, a blowing device constructed to be actuated by said lever, duct

connections between the blowing device and the spraying device, and operative connections between said lever and the blowing device, whereby the weight of a fowl on the 5 lever will operate the blower for the purposes described.

2. A lever, resilient means supporting the lever in predetermined initial position, a perch on the lever, a spraying device adjacent the perch for action upon a fowl when on the perch, a blowing device, connections between the blowing device and the spraying device, operative connections between said lever and blowing device, a vertically 10 movable food support adjacent the perch, and operative connections between the food support and said lever for upward movement of the support under downward movement of the lever.

20 3. In a device of the class described, a lever, a perch thereon, a vertically movable food support, located adjacent the perch, and operative connections between the lever and the food support for upward movement of the food support under downward movement of the lever.

4. In a device of the class described, a movable, resiliently supported perch, a vertically movable food support, and operative 30 connections between the perch and the food support for opposite movement of the two.

5. An article of the class described, comprising a base element, a perch mounted thereon for upward and downward movement, resilient means operative to hold the perch yieldably at the upper limit of its movement, a nozzle upward and downward movable with the perch and located closely adjacent thereto, a blower device, duct 35 connections between the blower and nozzle, and operative connections between said perch and the blower device.

40 6. A device of the class described comprising a base element, a puff ball, a fixed element at one side thereof, and an oscillatable element disposed at the opposite side of the puff ball and movable for compression thereof between the stationary and oscillatable element, a lever mounted on the oscillatable element, a perch at the outer end of the lever, a nozzle adjacent the perch, and

duct connections between said puff ball and nozzle.

7. A device of the class described, comprising a base element, a blower device comprising stationary and oscillatable members, and a member to be compressed by the oscillatable member, a lever mounted on the oscillatable member, a perch at the outer end thereof, a spraying device, and duct connections between said blower device and sprayer device.

8. A device of the character described comprising a base, a lever pivoted thereon, a blower device including a stationary and 65 an oscillatable element connected to the lever, said lever being hollow, duct connections between the interior of the lever and the blower device, a perch adjacent the outer end of the lever, a nozzle on the outer end of 70 the lever and resilient means tending to hold the lever at the upper limit of its movement.

9. In a fowl actuated poultry disinfecting device, a vertically movable nozzle carrying element, resilient means tending to hold it at the upper limit of its movement, a blower device, duct connections between the blower device and the nozzle device, operative connections between the blower and the 80 vertically movable element, a perch and means to support the perch adjacent the nozzle and pivotally for movement away from the nozzle under action of a fowl, and resilient means tending to hold the perch in 85 a predetermined initial position.

10. In a device of the class described, a resiliently supported lever comprising telescoped sections, means to secure the lever in extension adjustments, a perch at the outer part thereof, a spraying device thereadjacent, a blower device, duct means between the blower device and spraying device and operative connections between the blower 90 device and the lever.

In testimony whereof I have affixed my signature in presence of two witnesses.

DAVID B. BIRD.
